UNITED STATES PATENT OFFICE.

WILLIAM BULLITT CHAMPLIN, OF DALLAS, TEXAS.

DESIGN FOR A SCHEDULE-CARD FOR THE GAME OF FIVE HUNDRED.

No. 39,578.

Specification for Design.

Patented Sept. 22, 1908.

Application filed June 9, 1908. Serial No. 437,598. Term of patent 3½ years.

To all whom it may concern:

Be it known that I, WILLIAM BULLITT CHAMPLIN, a citizen of the United States, residing at Dallas, in the county of Dallas and State of Texas, have invented a new, original, and ornamental Design for a Schedule-Card for the Game of Five Hundred, of which the following is a specification, reference being had to the accompanying drawing, forming part thereof.

The figure is a plan view of a card, showing my new design as it will appear when printed thereon.

I claim:

The ornamental design for a schedule card for the game of five hundred as shown.

WILLIAM BULLITT CHAMPLIN.
